2 SHEETS-SHEET 2.

UNITED STATES PATENT OFFICE.

LESLIE L. WRIGHT, OF NEW YORK, N. Y.

FLOOR.

1,094,183.

Specification of Letters Patent. Patented Apr. 21, 1914.

Application filed April 23, 1913. Serial No. 763,019.

To all whom it may concern:

Be it known that I, LESLIE L. WRIGHT, a citizen of the United States, residing in the borough of Brooklyn, county of Kings, city 5 and State of New York, have invented an Improvement in Floors, of which the following is a specification.

My invention relates to floors for buildings and particularly such structures as 10 slaughter houses, storage warehouses, stables and the like, and its object is to provide a floor capable of withstanding very heavy traffic.

The invention consists of a frame composed of metallic sections forming a plurality of adjoining receptacles for asphalt, concrete or other suitable material, so constructed that the sections may be laid upon a suitable foundation connecting with each 20 other in such manner as to form a continuous flooring and whereby the respective sections will all be locked together by the filling material.

The details of the invention are hereininafter particularly described.

In the accompanying drawings: Figure 1 is a plan view of one of the metallic sections, showing some of the receptacles therein filled with asphalt or like material. Fig. 2 is a cross section on the broken line $\alpha-\alpha$ of Fig. 1. Fig. 3 is a plan view in smaller size showing a number of the sections assembled, and the receptacles containing the filling material. Fig. 4 is an inverted plan of 35 one of the metallic sections showing the receptacles filled with asphalt or like material, and Fig. 5 is a perspective view of a portion of one of the metallic sections, containing the filling material.

The sections are preferably cast from a suitable metal, the walls 1, 2, 3, 4, forming the receptacles 5, for the asphalt or similar material 6. These receptacles 5 are open both at the top and bottom. The bottom surfaces of the walls 1, 2, 3 and 4 in each section are cut away at spaced apart distances, forming openings 7 therein. The projecting members 8 are continuations of the walls on the respective sections, and these projections are also provided on their under surfaces with like openings 7, and it will be readily understood that when a num-

ber of the metallic sections are assembled as shown in Fig. 3, the projecting members 8 will be in alinement with the walls of the 55 receptacles 5 in the adjoining sections and complete the walls for a continuation of the receptacles to any desired extent, while the openings 7 in the walls provide communication between the receptacles at their lower 60 parts.

My improved floor may be laid upon any suitable foundation, but I prefer to employ a base 9, of wood, as shown in Figs. 1 and 2.

In laying a floor according to my invention, the desired number of metallic sections are placed upon a suitable foundation 9 and assembled as shown in Fig. 3 whereby continuous parallel and uniform rows of adjoining receptacles 5 are provided throughout the entire floor. I then pour into these receptacles asphalt or similar material in a heated state which material flows through the openings 7 in the walls of the receptacles and when hardened forms a solid connection 75 with the filling material in the respective receptacles, and at the same time locks all the metallic sections firmly together. When filling the receptacles 5, the material 6 is allowed to rise flush with the tops of the 80 walls 1, 2, 3 and 4 of the receptacles, and before becoming too hard, the top surface is smoothed and finished off by any suitable means, preferably by a trowel operated by hand. The floor thus constructed is very 85 firm and capable of withstanding heavy traffic as the upper surface of the metallic sections prevent undue wear upon the asphalt filling, and the filling material deadens sounds from the contact of vehicle 90 wheels with the metal sections.

Each metallic section is a separate casting but all the castings are alike, and while I prefer that each be made with twenty complete receptacles and three extended walls 95 on two opposite sides and on one end, with two extended walls on the other end, it will be readily understood that the size of the casting and number of receptacles therein may be varied without departing from my 100 invention.

I claim as my invention:

A floor for buildings, composed of a number of metallic sections each section being

cast in one piece comprising a plurality of adjoining hollow receptacles divided by parallel walls, with extending walls on each side of the casting, openings in the lower part of each wall, a material such as asphalt filling said receptacles and extending through said openings whereby the filling in all the receptacles is united together with the several metallic sections into one solid body.

Signed by me this 21st day of April 1913.

LESLIE L. WRIGHT.
